[57] CLAIM

The ornamental design for a combined footstool and
adjustable table, as shown.

DESCRIPTION

FIG. 1 is a plan view of a combined footstool and
adjustable table embodying the design of the invention;
FIG. 2 is a side elevational view of the combined foot-
stool and adjustable table of FIG. 1;

FIG. 3 is an end elevational view the opposite end being
a mirror image thereof;

FIG. 4 is a side elevational view of the combined foot-
stool and adjustable table of FIG. 1 showing the side
opposite to that shown in FIG. 2;

FIG. 5 is a plan view of the combined footstool and
adjustable table of FIG. 1 showing the table in an alter-
nate position;

FIG. 6 is a side elevational view of the combined foot-
stool and adjustable table in the position of FIG. 5; and
FIG. 7 is an end elevational view of the combined foot-
stool and adjustable table in the position of FIG. 5.
